DEVICE FOR MARKING CHEESES OR LIKE BLOCKS

Application filed March 24, 1932, Serial No. 601,002, and in Switzerland December 31, 1931.

This invention relates to devices for marking cheeses or like blocks by means of a stamp which is adapted to be placed on the centre portion of the block, and a printing appliance revoluble about the stamp.

With a known construction of this type the central stamp is provided with a shaft which is adapted to be bodily turned about the stamp and at the same time swung up and down and on which a conical rigid printing roll is mounted. In turning the shaft round the central stamp the roll performs a true rocking motion on the surface of the block for marking or printing the same. The surfaces of the various types of block-cheeses, however, being different, as there are cheeses made in round blocks the surfaces of which are flat or more or less bulged outwardly or irregularly curved or else slightly chamfered at the marginal portions, a uniform marking of the block by means of a rigid roll is rendered impossible particularly when the inclination of the shaft of the roll relatively to the surface is not adjustable.

According to this invention these drawbacks are eliminated by providing the printing appliance with two conical elastic printing rolls which in operating the appliance perform a true rocking motion on an inner and outer annular portion of the block and providing setting means for adjusting the level and the inclination of the axes of the rolls so as to enable the latter to adapt themselves to the irregularities of the surface of the block.

The setting means for the axes of the rolls permit also to equalize occasional irregularities in the printing rolls which may arise, particularly when the rolls are made by hand.

In the accompanying drawings two constructional forms of the invention are illustrated, by way of example only, in which

Fig. 1 shows a block-cheese indicating the printing rolls in the position thereon which they assume during the printing,

Fig. 2 is a broken-off cross-section of the block drawn to a larger scale and showing the printing device applied thereto,

Figs. 3 to 6 illustrate details of the device,

Fig. 7 is a partial bottom view of the central stamp of the device,

Fig. 8 is a disposition plan of the device as seen from above,

Figs. 9 and 10 are longitudinal sections of the two printing rolls,

Fig. 11 is a side elevation of a modification of the device,

Fig. 12 is a front elevation of Fig. 11, as seen from the left in this figure,

Fig. 13 is a plan view of the lower part of Fig. 11, and the

Figs. 14 to 16 are views of details on a larger scale.

Referring to the drawings, 1 denotes the cheese made in a round block, the upper surface of which is to be marked or imprinted by means of the device according to the invention. This device is provided with three main parts, i. e. a stamp S which is adapted to be placed on the centre portion of the block and two conical printing rolls 2 and 3 which are intended to perform a true rocking motion on an inner and an outer annular portion of the surface of the block for marking the cheese. The stamp S is formed with a cast body 4 to the underside of which a wooden frame 5 for accommodating the printing surface of the stamp is screwed by means of screws 6. The stamp is so constructed that it may readily adapt itself to any surface of a cheese even of considerable surface curvature. For obtaining the great flexibility requisite for this purpose circular segments 5' are combined with overlying concentric rings 5'' made of sponge rubber, air passages being provided between these elements which communicate with bores 7' in the wooden frame. The lowermost portion of the stamp is constituted by a rubber covering which is formed with raised portions which, as shown in Fig. 7, provide a design and corresponding reading matter. The resistance of the stamp to deformation is smallest in its centre portion and larger towards the peripheral portions of the same. The stamp is thus enabled to adapt itself to any surface curvature and to securely cling to the surface by suction action, whereby obliteration of the relatively fine lettering is avoided.

100

90

95

100

In the middle of the cast body 5 a bolt 8 is screwed from above to which a handle 9 is connected. On the bolt 8 is mounted a ring 10, so as to be rotatable thereon, to which 5 a forked supporting arm 11 is linked by means of screws 12, suchwise, that it is adapted to swing about a horizontal axis passing through these screws. Beyond the cast body 5 the forked supporting arm 11 is bent at 10 right angles and at the outer end of the supporting arm a boss 13 is provided comprising a bore in which a carrier bar 14 is mounted and secured against axial displacement by a cotter pin 15. The outer end of the 15 carrier bar 14 carries a control member 16 which is clamped to the bar 14 by means of a screw 17 and formed with a handle 18 which permits of turning the carrier bar 14 together with the printing rolls connected thereto about the central stamp. On a bolt 19 screwed in the control member 16 a supporting ring 20 is mounted to which two tripping rods 21 are secured. In their position shown in dotted lines in Fig. 3 the rods 25 21 serve for supporting the device, a bearing surface of the ring 20 resting in the corresponding position of the ring against a stop pin 22. In the position shown in full lines, however, the tripping rods are turned upwardly, one of the rods 21 being held by a clamping spring 23. In this position of the parts the printing device is adapted for printing, whereas with the rods 21 in the lowered position the rolls are withdrawn from the 30 surface of the cheese for the purpose of avoiding being deformed.

A split clamping member 24 is provided for each printing roll which is formed with a bore for accommodating the carrier bar 14 40 and clamped in position by means of a screw 25. The clamping member 24 is provided with a cylindrical neck 26 to which a mounting or bearing member 27 is clamped by means of a screw 28. Due to the fact that the 45 clamping member 24 after loosening the screw 25 can be turned about the carrier bar 14 and the mounting 27 after loosening the screw 28 about the clamping member 24, the mounting 27 is adapted to be adjusted in any 50 position relatively to the carrier bar 14. The clamping member 24 is also adapted to be displaced along the carrier bar 14 in order to adjust the two rolls 2 and 3 a required distance apart. In a bore of the mounting 27 55 a stub shaft 29 is rotatably mounted which is secured to a stirrup 30. To the stub shaft 29 by means of a screw 31 a lever arm 32 is clamped, the outer end of which pivotally carries a lug 33 provided with a screw bore. 60 Through the lug 33 and a lug 34 also provided with a screw bore and pivotally carried by the mounting 27, a spindle 35 provided with left hand and right hand thread portions and with wings 36 for turning the 65 same by hand is passed. By screwing the

spindle 35 in or out respectively the lever arm 32 and the stub shaft 29 connected to the stirrup 30 carrying the respective printing roll are correspondingly rotated. The rotational displacement of the stirrup 30 effected by the screw spindle 35 serves for adjusting the axis of the respective roll in order to approximately adapt the inclination of the axis to the inclination of the surface of the cheese. The fine adjustment is 70 brought about by the body of the rolls being of elastic construction. Moreover, adjusting the axis of the outer roll in a fixed position is provided for, when for example marking a cheese of a smaller diameter is required, as 75 in this case with the stirrup 30 left free to move, the roll 3 were apt to tilt on the edge of the block 1 which would render a uniform printing impossible. The stirrup 30 is provided with holes 37 one of which is formed 80 with a screw thread for engaging a bearing shaft 38 provided with wings 39 for the printing rolls 2 and 3 respectively. The bearing shaft 40 of each inking roller 41 is mounted at one end in a bearing member 42 which 85 is guided in a slot 43 of the stirrup 30 and adjustable by means of a set screw 44. At the other end the bearing shaft 40 is guided in a slot 45 of the stirrup 30 and the inking rollers 41 are urged against the printing 90 rolls 2, 3 respectively by a spring 46 acting on the stirrup 30 and passed round a guide disc 47 on the shaft 40. At the outer end the shaft 40 is bent in the form of a crank 95 to permit turning the shaft by hand for supplying printing color to the printing rolls. 100

The conical printing rolls 2, 3 are provided with inner metal tubes 51 comprising bushings 48 in which the bearing shafts 38 are mounted. On one side a conical wooden member 49 is secured to the tube 51 by screws 50 and in line with the member 49 two or three conical bosses 52 are mounted on the tube 51 through intervening bandages, not shown, for example of insulating material 105 and wrapped around the tube 51, the bosses in turn being made of vulcanized rubber including inserts of sponge rubber. On the bosses 52 and the wooden member 49 layers 53 are placed which consist of longitudinal 110 strips of red soft sponge rubber. Above and between the layers 53, layers 54 are placed which consist of transversely arranged rings also made of red sponge rubber. Between the individual rings 54 annular spaces 55 are 115 formed and between the layers 53 longitudinally extending spaces. All these spaces communicate with each other and with passages 56 by way of which the entrapped air in the interior of the roll can escape when the 120 roll is compressed on one side and reenter through the corresponding passages on the upper side of the roll, when the pressure on the latter is relieved. In this manner the 125 elasticity of the roll is substantially in- 130

creased, the layers being adapted to yield laterally, when compressed, so as to assume an enlarged shape. On the layers 53 and 54 one or more mantles 57 of red soft sponge rubber are placed on which a rubber covering 58 provided with printing portions for reading matter is arranged. Rolls made in this manner are adapted to fit the surface of the cheese snugly due to the elasticity of their parts, as will be seen in Fig. 10 in which the curved surface of the cheese is designated by 59 (see also Fig. 1). The chain dotted lines in the interior of the roll shown in Fig. 10 indicate the manner in which the entrapped air in the porous sponge rubber leaves the roll, when it is pressed against a support, and reenters the roll, when the pressure is relieved. Even if the rolls be made by hand and therefore not perfectly alike in all parts of the construction, it is nevertheless possible to imprint a block-cheese with the aid of the described device in uniform manner, the rolls proper being extremely elastic and adjustable with respect to their own bearing shafts as well as to the carrier bar 14.

The printing of a cheese is executed by means of this device in such manner that at first the stamp S is inked in with the aid of a stamp pad and then placed on the middle portion of the cheese and held in this position by applying the one hand to the handle 9.

By this setting of the stamp S the middle portion of the cheese is printed. The other hand is applied to the handle 18 of the device by means of which after the stamp S is set in place the printing rolls 2, 3 arranged on both sides of the carrier bar 14 are lowered until they rest against the surface of the cheese 1. By properly adjusting the wing screws 35, 36 the inclination of the axes of the rolls is then adapted to the curvature of the surface of the cheese. Thereafter the surface may be imprinted by turning the carrier bar 14 by means of the handle 18 about the central stamp S, whereby the rolls perform a true rocking motion on the surface of the cheese, so as to print along an annular portion on the surface of the cheese. On the completion of a full revolution of the bar 14 round the cheese the printing operation is finished and the whole device removed from the cheese with the aid of the handles 9 and 18.

Alternatively instead of setting the device on the cheese and turning the rolls round the same as described, the roll carriages may be left at standstill and the cheese which is placed on a rotatable table turned past the rolls.

An arrangement of this kind is shown in the Figs. 11 to 16, wherein 70 denotes the rotatable table which is suitably provided with a mark or stop for limiting its rotational movement to maximum 360°. The table 70 is formed with a central boss 71 to which a chain wheel 72 is secured. The boss 71 is

guided in a bore of a traverse 73 of a frame 74 standing on two front legs 75 provided at their lower ends with wheels 76 and a rear leg 75 abutting on the floor with a blunt end. On the underside of the traverse 73 beneath the chain wheel 72 a pair of coaxially disposed interconnected chain wheels 77, 78 is mounted, the wheel 78 being operatively connected with the wheel 72 by a driving chain and the wheel 77 taking its drive by means of another chain from a chain wheel 79 mounted at the rear end of the frame 74 on a common spindle with a hand wheel 80. By turning the hand wheel 80 the table 70 is correspondingly turned at slower speed, thereby traveling with rollers 81 arranged on its underside on a supporting plate disposed on the upper side of the frame 74. At the extreme rear end of the frame 74 a shaft stub 82 is provided which is adapted to receive a handle, 85 not shown, for raising the leg 75 off the floor and wheeling the device to some other place of application when this is desired.

To the upper end of the leg 75 a connecting member 83 is clamped which is provided with a further clamping connection for receiving a vertical rack rod 84 on which a cantilever arm 85 is longitudinally displaceable through the intermediary of a guide block 86 provided with a hand-operated pinion engaging in the rack teeth. A clamping member 87 is provided for securing the block 86 in position on the rod 84, as required, and for facilitating the raising of the arm 85, by means of the rack gear, the arm is counterbalanced by means of a tension spring 88 anchored to the lower end of the leg 75 and exerting an upward pull on the arm 85 through the medium of a flexible tension member 89 passing over a guide roller at the top of the rod 84. Alternatively, instead of the spring 88 a counterweight may be used.

On the free end of the cantilever arm 85 a mounting member 90 is fixed, so that the stamp S which is rotatably mounted therein by means of a pin is centrally disposed above the table 70. Between the member 90 and a hand lever 92 a coiled compression spring 93 is interposed through the intermediary of an abutment member 94 which is constructed so as to provide an elastic connection between the stamp S and the mounting member 90 without hindering relative rotation between these last-mentioned members, when in the lowered position of the cantilever arm 85 it is desired to turn the stamp S relatively to the cheese 1 placed on the table 70, before setting the stamp on the middle portion of the cheese by depression of the hand lever 92. After the stamp S has been set in proper position on the cheese, the carrier bar 14 for the printing rolls 2, 3, the outer end of which is regulatably suspended from an arm 95 fixed to the mounting member 90 by means of a stirrup 96 130

and a setting pin 97, is adapted to the curvature of the surface of the cheese by inserting the pin in a corresponding bore of the stirrup 96. For this purpose the inner end of the carrier bar 14 is mounted in a lever arm 98 similar to the supporting arm 11 of the previous example of the device and rotatably mounted on the horizontal cantilever arm 85. Otherwise, the printing rolls and the adjusting means for the same as well as the means for supplying the rolls with printing color are of equal construction as afore-described.

I claim:

1. In a device for marking cheeses or like blocks of the type described, in combination, a stamp adapted to be set on the middle portion of the surface to be marked of the block, a printing appliance for printing the block around the central impression to be made with said stamp, mounting means operatively interconnecting said stamp and said printing appliance and providing a pivot joint between these two parts, two conical elastic printing rolls provided in said printing appliance different radial distances apart from said stamp, regulating means for said printing appliance for adjusting the level and the inclination of the axes of said elastic printing rolls with respect to the block and enabling said rolls to adapt their surfaces to the irregularities of the surface of the block, and means for turning said printing appliance and said block relatively to each other about the axis of said pivot joint for causing said printing rolls to perform a true rocking motion on an inner and an outer annular portion of the block.

2. In a device for marking cheeses or like blocks of the type described, in combination, a stamp adapted to be set on the middle portion of the surface to be marked of the block, a printing appliance for printing the block around the central impression to be made with said stamp, mounting means operatively interconnecting said stamp and said printing appliance and providing a pivot joint between these two parts, two conical elastic printing rolls provided in said printing appliance different radial distances apart from said stamp, a carrier for said printing rolls receiving said rolls on both sides of the same and connected with said mounting means intercalated between said stamp and said printing appliance, regulating means for said printing appliance for adjusting the level and the inclination of the axes of said elastic printing rolls with respect to the block and enabling said rolls to adapt their surfaces to the irregularities of the surface of the block, and means for turning said printing appliance and said block relatively to each other about the axis of said pivot joint for causing said printing rolls to perform a true rocking motion on an inner and an outer annular portion of the block.

3. In a device for marking cheeses or like blocks of the type described, in combination, a stamp adapted to be set on the middle portion of the surface to be marked of the block, a printing appliance for printing the block around the central impression to be made with said stamp, mounting means operatively interconnecting said stamp and said printing appliance and providing a pivot joint between these two parts, two conical elastic printing rolls provided in said printing appliance different radial distances apart from said stamp, a carrier for said printing rolls receiving said rolls on both sides of the same, a supporting member rotatably accommodating said carrier, a horizontal pivot connection arranged between said supporting member for said carrier and said mounting means intercalated between said stamp and said printing appliance and adapting said supporting member to be rocked in the vertical direction, regulating means for said printing appliance for adjusting the level and the inclination of the axes of said elastic printing rolls with respect to the block and enabling said rolls to adapt their surfaces to the irregularities of the surface of the block, and means for turning said printing appliance and said block relatively to each other about the axis of said pivot joint for causing said printing rolls to perform a true rocking motion on an inner and an outer annular portion of the block.

4. In a device for marking cheeses or like blocks of the type described, in combination, a stamp adapted to be set on the middle portion of the surface to be marked of the block, a printing appliance for printing the block around the central impression to be made with said stamp, mounting means operatively interconnecting said stamp and said printing appliance and providing a pivot joint between these two parts, two conical elastic printing rolls provided in said printing appliance different radial distances apart from said stamp, a carrier for said printing rolls, a stirrup for each printing roll adapted to rotatably accommodate the roll, said stirrup being disposed on different sides of said carrier, adjusting means interposed between each stirrup and said carrier and adapted to vary the relative inclination of said carrier and the axes of said elastic printing rolls for regulating the inclination of said axes with respect to the block, setting means for said printing appliance for regulating the level of the axes of said elastic printing rolls and enabling in conjunction with said adjusting means to adapt the surfaces of said rolls to the irregularities of the surface of the block and means for turning said printing appliance and said block relatively to each other about the axis of said pivot joint for causing said printing rolls to perform a true rocking

motion on an inner and an outer annular portion of the block.

5. In a device for marking cheeses or like blocks of the type described, in combination, a stamp adapted to be set on the middle portion of the surface to be marked of the block, a printing appliance for printing the block around the central impression to be made with said stamp, mounting means operatively interconnecting said stamp and said printing appliance and providing a pivot joint between these two parts, two conical elastic printing rolls provided in said printing appliance, different radial distances apart from said stamp, a carrier for said printing rolls, a bearing member connected with said carrier for each printing roll, a stirrup for each printing roll, adapted to rotatably accommodate the roll and disposed respectively on different sides of said carrier, a stub shaft secured to each stirrup and rotatably mounted in the related bearing member, adjusting means interposed between said stub shafts and the related bearing members for regulating the relative inclination of said carrier and the axes of said elastic printing rolls by rotation of said stub shafts in the related bearing members, setting means for said printing appliance for regulating the level of the axes of said elastic printing rolls and enabling in conjunction with said adjusting means to adapt the surfaces of said rolls to the irregularities of the surface of the block, and means for turning said printing appliance and said block relatively to each other about the axis of said pivot joint for causing said printing rolls to perform a true rocking motion on an inner and an outer annular portion of the block.

40. 6. In a device for marking cheeses or like blocks of the type described, in combination, a stamp adapted to be set on the middle portion of the surface to be marked of the block, a printing appliance for printing the block around the central impression to be made with said stamp, mounting means operatively interconnecting said stamp and said printing appliance and providing a pivot joint between these two parts, two conical elastic printing rolls provided in said printing appliance different radial distances apart from said stamp, a carrier for said printing rolls, a bearing member connected with said carrier for each printing roll, a stirrup for each printing roll, adapted to rotatably accommodate the roll and disposed respectively on different sides of said carrier, a stub shaft secured to each stirrup and rotatably mounted in the related bearing member, a lever arm secured on said stub shaft, screw means interposed between said lever arms on said stub shafts, and the related bearing members for regulating the relative inclination of said carrier and the axes of said elastic printing rolls by rotation of said stub shafts in the

related bearing members, setting means for said printing appliance for regulating the level of the axes of said elastic printing rolls and enabling in conjunction with said adjusting means to adapt the surfaces of said rolls to the irregularities of the surface of the block, and means for turning said printing appliance and said block relatively to each other about the axis of said pivot joint for causing said printing rolls to perform a true rocking motion on an inner and an outer annular portion of the block.

7. In a device for marking cheeses or like blocks of the type described, in combination, a stamp adapted to be set on the middle portion of the surface to be marked of the block, a printing appliance for printing the block around the central impression to be made with said stamp, mounting means operatively interconnecting said stamp and said printing appliance and providing a pivot joint between these two parts, two conical elastic printing rolls provided in said printing appliance, different radial distances apart from said stamp, a carrier for said printing rolls, a bearing member connected with said carrier for each printing roll, a clamping member provided on said carrier for each bearing member and adapted to adjust said bearing members on said carrier in different relative positions to said stamp, a stirrup for each printing roll, adapted to rotatably accommodate the roll and disposed respectively on different sides of said carrier, a stub shaft secured to each stirrup, and rotatably mounted in the related bearing member, a lever arm secured on said stub shaft, screw means interposed between said lever arms on said stub shafts, and the related bearing members for regulating the relative inclination of said carrier and the axes of said elastic printing rolls by rotation of said stub shafts in the related bearing members, setting means for said printing appliance for regulating the level of the axes of said elastic printing rolls and enabling in conjunction with said adjusting means to adapt the surfaces of said rolls to the irregularities of the surface of the block, and means for turning said printing appliance and said block relatively to each other about the axis of said pivot joint for causing said printing rolls to perform a true rocking motion on an inner and an outer annular portion of the block.

8. In a device for marking cheeses or like blocks of the type described, in combination, a stamp adapted to be set on the middle portion of the surface to be marked of the block, a printing appliance for printing the block around the central impression to be made with said stamp, mounting means operatively interconnecting said stamp and said printing appliance and providing a pivot joint between these two parts, two conical elastic printing rolls provided in said printing ap-

- pliance, different radial distances apart from said stamp, parallel layers of an elastic material adapted to entrap air and constituting the body of said printing rolls, air passages provided in said layers for the entrance and exit of air to and from the interior of said rolls on deformation of the same for increasing the elasticity of the rolls, regulating means for said printing appliance for 5 adjusting the level and the inclination of the axes of said elastic printing rolls with respect to the block and enabling said rolls to adapt their surfaces to the irregularities of the surface of the block, and means for turning said 10 printing appliance and said block relatively to each other about the axis of said pivot joint for causing said printing rolls to perform a true rocking motion on an inner and an outer annular portion of the block.
- 15 9. In a device for marking cheeses or like blocks of the type described, in combination, a stamp adapted to be set on the middle portion of the surface to be marked of the block, a printing appliance for printing the block around the central impression to be made 20 with said stamp, mounting means operatively interconnecting said stamp and said printing appliance and providing a pivot joint between these two parts, two conical elastic printing 25 rolls provided in said printing appliance, different radial distances apart from said stamp, a conical wooden core member for said printing rolls, conical bosses of vulcanized rubber aligning with said core member, parallel 30 strips of sponge rubber longitudinally applied to said core member and said bosses, parallel rings of sponge rubber transversely applied to said strips and intermeshing with the same, air passages formed between said 35 intermeshing rings and strips in longitudinal and transverse annular disposition in said printing rolls, at least one mantle of sponge rubber overlying said core member and said bosses, an exterior rubber covering arranged 40 on said mantle and providing the printing surface for said rolls, regulating means for said printing appliance for adjusting the level and the inclination of the axes of said elastic printing rolls with respect to the block, 45 and enabling said rolls to adapt their surfaces to the irregularities of the surface of the block, and means for turning said printing appliance and said block relatively to each other about the axis of said pivot joint 50 for causing said printing rolls to perform a true rocking motion on an inner and an outer annular portion of the block.
- 55 10. In a device for marking cheeses or like blocks of the type described, in combination, a stamp adapted to be set on the middle portion of the surface to be marked of the block, segmental and annular portions of sponge rubber constituting the body of said stamp and increasing in number towards the centre 60 thereof, air passages formed between said 65 segmental and annular portions and adapted to entrap air in increasing quantity towards the centre of the stamp for providing a ready adaptation of the printing surface of the stamp to the surface curvatures of the block, 70 a printing appliance for printing the block around the central impression to be made with said stamp, mounting means operatively interconnecting said stamp and said printing appliance and providing a pivot joint between these two parts, two conical elastic printing 75 rolls provided in said printing appliance different radial distances apart from said stamp, regulating means for said printing appliance for adjusting the level and the inclination of the axes of said elastic printing rolls with respect to the block and enabling said rolls to adapt their surfaces to the irregularities of the surface of the block, 80 and means for turning said printing appliance and said block relatively to each other about the axis of said pivot joint for causing said printing rolls to perform a true rocking motion on an inner and an outer 85 annular portion of the block.
- 90 11. In a device for marking cheeses or like blocks of the type described, in combination, a rotatable table for accommodating the block with its surface to be imprinted on top, a stamp adapted to be set on the middle portion of said surface of the block, a printing appliance for printing the block around the central impression to be made with said stamp, mounting means operatively interconnecting said printing appliance and said 95 stamp and resiliently carrying the latter and providing a pivot joint between these two parts, two conical elastic printing rolls rotatably mounted in said printing appliance different radial distances apart from said stamp, adjusting means for varying the inclination of the axes of said printing rolls for regulating the inclination of said axes with respect to the block, a cantilever arm supporting said mounting means for said printing appliance and said stamp, setting means for said cantilever arm for varying the height of said arm above said table for regulating the level of the axes of said elastic printing rolls and enabling in conjunction with said adjusting means to adapt the surfaces of said rolls to the irregularities of the surface of the block, and means for turning said printing appliance and said rotatable table accommodating the block relatively to each other about the axis of said pivot joint for causing said printing rolls to perform a true rocking motion on an inner and an outer annular portion of the block.
- 100 12. In a device for marking cheeses or like blocks of the type described, in combination, a rotatable table for accommodating the block with its surface to be imprinted on top, a stamp adapted to be set on the middle portion of said surface of the block, a printing 105 110 115 120 125 130

appliance for printing the block around the central impression to be made with said stamp, mounting means operatively interconnecting said printing appliance and said stamp and resiliently carrying the latter and providing a pivot joint between these two parts, two conical elastic printing rolls rotatably mounted in said printing appliance different radial distances apart from said stamp, a carrier for said printing rolls receiving said rolls on both sides of the same, a supporting member rotatably accommodating said carrier, a horizontal pivot connection arranged between said supporting member for said carrier and said mounting means and adapting said carrier to swing in the vertical direction together with said rolls, adjusting means for varying the inclination of the axes of said printing rolls for regulating the inclination of said axes with respect to the block, a cantilever arm supporting said mounting means for said printing appliance and said stamp, setting means for said cantilever arm for varying the height of said arm above said table for regulating the level of the axes of said elastic printing rolls and enabling in conjunction with said adjusting means to adapt the surfaces of said rolls to the irregularities of the surface of the block, and means for turning said printing appliance and said rotatable table accommodating the block relatively to each other about the axis of said pivot joint for causing said printing rolls to perform a true rocking motion on an inner and an outer annular portion of the block.

13. In a device for marking cheeses and like blocks of the type described, in combination, a stamp adapted to be set on the middle portion of the surface of the block to be marked, a printing appliance for printing the block around the central impression to be made with said stamp, mounting means operatively interconnecting said stamp and said printing appliance and providing a pivot joint between these two parts, two conical elastic printing rolls provided in said printing appliance different radial distances apart from said stamp, regulating means for said printing appliance for adjusting the level and the inclination of the axes of said elastic rolls with respect to the block and enabling said rolls to adapt their surfaces to the irregularities of the surface of the block, and means for causing said printing rolls to perform a true rocking motion on an inner and an outer annular portion of the block with the stamp pressed in position on the block by virtue of said pivot.

60 In testimony whereof I have signed my name to this specification.

FRITZ MOESCHLIN.
